UNITED STATES PATENT OFFICE.

JOHN HENRY WHITEHEAD, OF LEEDS, COUNTY OF YORK, ENGLAND.

ROLLER-STAND FOR COMBING-MACHINES.

SPECIFICATION forming part of Letters Patent No. 314,406, dated March 24, 1885.

Application filed November 24, 1884. (No model.) Patented in Eng'nd June 30, 1885, No. 3,248.

To all whom it may concern:

Be it known that I, JOHN HENRY WHITEHEAD, of Leeds, in the county of York, England, have invented a new and useful improvement 5 in machinery for combing wool, cotton, flax, silk, and other fibrous substances, which improvement is fully set forth in the following specification, reference being had to the accompanying drawings.

10 My improvement has reference to combing-machines, in which drawing-off rollers and leathers are employed for drawing off the fibers from the pins of the combs, the object of my improvement being to provide an arrangement whereby the roller-stands can be 15 retained in position, and also readily released when the leathers require changing, or when anything occurs in which the rollers and leathers require attention.

20 Hitherto the roller-stands have been carried and fixed together by screws or bolts, so that when the leathers or rollers required removing or otherwise attending to a considerable loss of time was caused in unscrewing or 25 releasing the stands and in stopping the machine.

Figure 1 is a front elevation, and Fig. 2 is a plan showing my improvement.

a is the bottom stand, having an upright bar, *b*, attached thereto by means of screws or bolts *c*, in the ordinary way. The upper stand, *d*, is secured to the vertical bar *b* by means of the stud *e* and catch *f*, the stud *e* passing through an open slot in the top of the bar *b*. By this arrangement the top stand, *d*, is easily and 35 quickly released by withdrawing the catch *f* away from the stud *e*, (which it embraces when the stand is fixed in position, as shown.) This operation is effected by the attendant, so that the leathers and rollers can be changed or removed or otherwise attended to when required without difficulty or much loss of time. The slot in the catch *f* is formed to such a curve 40 that it tightens against the stud *e* when pushed over the latter, being thereby firmly retained 45 in position.

I claim as my invention—

The combination, with the rollers and stationary roller-stand *a*, of the fixed upright bar *b*, the catch *f*, stud *e*, and top stand, *d*, 50 substantially as set forth.

JOHN HENRY WHITEHEAD.
